DESIGN FOR A TOILET ROLL RECEPTACLE

John N. Wood, Media, Pa.

Application October 28, 1946, Serial No. 134,329

Term of patent 14 years

(Cl. D4—3)

To all whom it may concern:

Be it known that I, John N. Wood, a citizen of the United States, residing in Media, Delaware County, Pennsylvania, have invented a new, original, and ornamental Design for a Toilet Roll Receptacle, of which the following is a specification, reference being had to the accompanying drawings, forming a part thereof.

Fig. 1 is a front view in perspective of a toilet roll receptacle, showing my new design, and

Fig. 2 is a rear perspective view of the receptacle.

I claim:

The ornamental design for a toilet roll receptacle, as shown.

JOHN N. WOOD.
